UNITED STATES PATENT OFFICE.

FRITZ HAUDEL, OF BOSTON, MASSACHUSETTS.

DESIGN FOR A FRAME FOR GENERATING SETS.

SPECIFICATION forming part of Design No. 29,375, dated September 20, 1898.

Application filed August 18, 1898. Serial No. 688,932. Term of patent 14 years.

To all whom it may concern:

Be it known that I, FRITZ HAUDEL, a citizen of the United States, residing at Boston, in the county of Suffolk and State of Massachusetts, have invented and produced a certain new and original Design for a Frame for Generating Sets; and I do hereby declare the following to be a full, clear, and exact description of the invention, such as will enable others skilled in the art to which it appertains to make and use the same.

Referring to the accompanying drawings, Figure 1 is a front elevation. Fig. 2 is a plan view, and Figs. 3 and 4 are end elevations.

As shown in the drawings, the leading and material features of my design are described as follows:

A is a rectangular base. From opposite sides thereof rise two columns B B, which are inclined toward each other, joined together at their upper ends, and surmounted by a cy-

lindrical body C. A member D, consisting of an elongated open frame, is transversely disposed with relation to and immediately adjoining the extension E on one end of the base A, and struts F are interposed between the upper part of the member D and the columns B B. A yoke G connects the upper and lower parts of the member D on the opposite side to the base A.

Having thus described my invention, I claim as new and desire to secure by Letters Patent—

The design for a frame for a generating set substantially as shown and described.

In testimony whereof I have hereunto affixed my signature in presence of two witnesses.

FRITZ HAUDEL.

Witnesses:

T. HART ANDERSON,
HORACE VAN EVEREN.
